CORPORATION OF DELAWARE.

SIGN CONSTRUCTION

1,192,982.

Specification of Letters Patent. Patented Aug. 1, 1916.

Application filed October 12, 1914. Serial No. 866,344.

To all whom it may concern:

Be it known that we, FREDERICK A. BRISTOL and PAUL J. SCHARRINGHAUSEN, citizens of the United States, residing at Des 5 Plaines, in the county of Cook and State of Illinois, have invented certain new and useful Improvements in Sign Constructions; and we do hereby declare the following to be a full, clear, and exact description of the 10 invention, such as will enable others skilled in the art to which it appertains to make and use the same.

This invention comprehends new and useful improvements in signs of the electrically 15 illuminated type which consist of a number of letters, and resides in the provision of novel construction for forming separate illuminated letters that is simple, inexpensive to manufacture and reliable and effi- 20 cient.

Another object of importance is to provide a supporting structure for one or more illuminated letters that co-operates with a letter or letters so as to form a simple, durable and effective illuminated sign, and 25 which is constructed so that a sign of any desired size and number of letters may be disposed readily and easily assembled.

Another object is to generally improve 30 the illuminated sign structure of the character described so as to render it more reliable and efficient in operation, inexpensive to manufacture and maintain in operative condition.

The above and additional objects are accomplished by such means as are illustrated in the accompanying drawings, described in the following specification and then more particularly pointed out in the claims.

With reference to the drawings, wherein we have illustrated the preferred embodiment of our invention as it is reduced to practice, and throughout the several views of which similar reference numerals designate corresponding parts, Figure 1 is a detail perspective view of the metallic frame 45 piece of the letter supporting base for the sign structure, Fig. 2 is a detail cross sectional view of the wood base block mounted in the base plate, Fig. 3 is a plan view shown partly broken away of the base block showing the electrical connecting members there- 50 in, Fig. 4 is a side elevation of a sign constructed in accordance with our invention,

and Fig. 5 is a horizontal sectional view taken on line 5—5 of Fig. 4 showing the details of construction of one of the letters of the sign.

Referring to the drawings by characters of reference, the numeral 1 designates as an entirely a metallic base frame for the letter supporting base of our invention that comprises a metallic body plate 2, an upstanding rear wall 3 formed integral with the body plate and extending for a distance equivalent to the width thereof, and an upwardly and inwardly inclined front wall 4 formed on the edge of the body plate 2 opposite to that on which the wall 3 is arranged and which terminates at its upper edge in a plane with the upper edge of the wall 3. A block of wood or similar insulating material 5 is inclined upon one side as at 6 in such manner as to fit within the

metallic base 1 so that the block 5 is securely retained within said metallic base 1. This block 5 fits snugly within the frame 4 and is flush at its top with the frame 1 as clearly shown in Fig. 6.

The block 5 is formed with horizontally disposed longitudinal openings or passages 7, two in number, receive metallic rods 8. The rods 8 are disposed each with certain ends projecting beyond one face of the block 5 and with the other ends spaced from

the adjacent end of the opening or passage 7 so that when one or more blocks are arranged in connection with one another, the members 8 will form continuous conductors for a purpose of supplying electricity to the

lamps of the sign as will be later more fully described. A pair of apertures 9 is formed vertically within the upper part of the block 5, and each aperture communicates with one of the openings or passages 7 and extends for a short distance below the passages or openings. Apertures are formed through the rods 8 and align with the openings or apertures 9 in the block 5. Vertical rods 10 are mounted in the apertures 9 and in the base plate, Fig. 3 is a plan view shown partly broken away of the base block showing the electrical connecting members there- 50 in, Fig. 4 is a side elevation of a sign constructed in accordance with our invention,

illuminable letter as will be later more fully described.

With reference to the foregoing description and accompanying drawings, it will be observed that an illuminated sign formed of a number of units, each unit comprising an illuminated letter, a frame 1, block 5 and pair of rods 8 and 10 may be formed with our improved sign structure. The rods 10 provide means for supporting an illuminated sign letter and for connecting an electric lamp or lamps therein with an electrical circuit. It will be seen that a plurality of bases for letters may be easily and reliably connected with one another so that a sign of as many letters as desired may be formed. The rods 8 in each block of a sign composed of a number of blocks extend into each other and contact with one another, so that continuous conducting lines are provided.

We provide a sign letter 11, which consists of a metallic frame piece 12 of metal. The frame piece 12 may be of any desired shape dependent upon the letter to be formed and is filled to a point flush with the side edges at the open face thereof with porcelain 13 or some other similar material. A front for the open face of the frame 12 consisting of a covering of transparent material 14, for example, glass, isinglass or the like is provided. This strip 14 is approximately semi-circular in cross section and has its free edges disposed within the porcelain 13 and in engagement with the inner side faces of the frame 12. It will be readily seen, that an illuminated letter constructed as described will be durable and effective, and may be cheaply and readily assembled and disassembled.

40 Embedded within the porcelain 13 is a lamp socket 15. Any number of these lamp sockets may be employed, the outer ends of the sockets being flush with the outer face of the filling or porcelain 13 while the inner 45 end rests upon the strips of insulating material 16. The rods 10 are extended through the letter frame 12 into the filling or porcelain 13 at any desired place dependent upon the size of the letter and the position in 50 which it is to be secured and served to support the letter. The rods 10 are also connected with each of the lamp sockets in any suitable manner so as to provide a circuit for an electric lamp 16 mounted within the socket 15. The rods 10 may be connected with the lamp 16 in any suitable manner however, in series or multiples, and it has not been thought necessary to illustrate electrical connection between the lamp 60 or socket therefor, with the rod 10.

With reference to the foregoing description and accompanying drawings it will be observed that we have provided an illuminated sign construction that will enable an 65 expeditious setting up of an electric sign.

In practice, we have found that the form of our invention, illustrated in the drawings and referred to in the above description, as the preferred embodiment, is the most efficient and practical; yet realizing that the 70 conditions concurrent with the adoption of our device will necessarily vary, we desire to emphasize the fact that various minor changes in details of construction, proportion and arrangement of parts may be resorted to, when required, without sacrificing any of the advantages of our invention, as set forth in the appended claims.

What is claimed is:—

1. In a device of the class described in combination, a metallic trough like frame having a contour conforming to a predetermined letter of the alphabet, a porcelain filler substantially filling said frame, a plurality of lamp sockets carried by said porcelain filler and constructed with the outer end thereof substantially flush with the outer face of said porcelain filling, a transparent cover of the outline of said predetermined letter of the alphabet, said transparent cover being substantially semicircular in cross section, said transparent cover also having its walls spaced at the edges to substantially correspond to the width between the edges of said trough like frame to enable the said transparent cover to set upon said frame with its edges within the edges of said frame, and a supporting base for said letter.

2. In a device of the class described in combination, a metallic frame of trough like cross section having a contour corresponding to a letter of the alphabet, a filler of non-conducting material substantially filling said trough like frame, said filling material being provided with a plane surface on the front thereof substantially flush with the plane determined by the front edges of said trough like frame, a plurality of electric lamp sockets mounted within said insulating filler, a transparent covering of a substantially semi-circular cross section extending from edge to edge of said trough like portions of said frame, said transparent covering being spaced from said facing a sufficient distance to accommodate electric lights mounted within said sockets, and a base for supporting said frame.

3. In an electric sign in combination, an individual letter outline provided with electric lamps, terminal members connected with said lamps and projecting from said letter, a base member having sockets therein constructed to receive the terminal members and detachably support said letter, a plurality of electrical conductors within said base, each conductor passing through one of said socket members, and coupling devices formed on each end of said electrical conductors, whereby a plurality of bases may be detachably coupled together to form con-

tinuous common conductors for supplying electricity to a plurality of letters.

4. An electric sign comprising a base composed of a plurality of members, means forming a part of an electric circuit for connecting said members together, a plurality of individual letter outlines provided with electric lamps, terminal members projecting from each of said letter outlines, and means carried by each of the base members

for detachably receiving said terminals, said letters and said bases each being relatively and individually interchangeable.

In testimony whereof we affix our signatures in presence of two witnesses.

FREDERICK A. BRISTOL.

PAUL J. SCHARRINGHAUSEN.
